AIR GAGE

William A. Minix, Detroit, Mich., assignor to
Freeland Gauge Company, Detroit, Mich.
Original application June 25, 1963, Ser. No. 290,526, now
Patent No. 3,170,318, dated Feb. 23, 1965. Divided
and this application Nov. 25, 1964, Ser. No. 413,682
2 Claims. (Cl. 73—37.5)

This application, a division of Ser. No. 290,526 of 10
June 25, 1963, now Patent Number 3,170,318, discloses
a cabinet type multiple column air flow gage, one important element of which is a sectional valve body unit
comprising side by side separate valve bodies secured together into a unit, each having its own built in bleed 15
valve and by pass valve, and its own air tube, return air
flow conduit, gage element, outlet conduit, and air supply
conduit, with such unit supporting cabinet sides in turn
supporting other parts of the device.

A preferred form is shown in the following specification 20
and appended drawings.

In these drawings:

FIG. 1 is a partly broken away front elevational view
of the present air flow gage device providing a plurality
of separate indicating columns for a plurality of simultaneous 25
gaging operations.

FIG. 2 is a partly broken away rear elevational view
thereof.

FIG. 3 is a partly broken away plan view thereof, to an 30
enlarged scale.

FIG. 4 is a vertical section on lines 4—4 of FIG. 1, to
an enlarged scale.

FIG. 5 is an enlarged section of the valve body per se.
The air gage housing or cabinet shown includes base 35
11 upon which is mounted a sectional valve body 10 comprising
adjacent separate valve bodies 12 with end spacers 15, and
secured to the base by screws 17. Pins 13—14 and
fasteners 16 connect the separate valve bodies 12.

Cabinet side members 18 connect to and are connected
by said valve body unit 10 by fasteners 19. Manifold
covers 20 are secured at 21 to sides 18, and include circular
bosses 22 which project within opposite ends of
air manifold 23, sealed by O-rings 24. Nipple 25, FIG. 4
supplies air under pressure to manifold 23.

The cabinet includes rear wall 26 secured by fasteners
27 to manifold covers 20. Removable top 28 extends
along the upper back portion of the housing as at 28' and
includes a depending front wall portion 29.

An upper tube support block 30 with end mounting
brackets 31 is between side walls 18 and is secured thereto
by fasteners 31', FIG. 2. Top 28 is secured to tube support 30 by fasteners 60'. 50

Tube support 30 has longitudinally spaced vertical
bores, FIG. 4, within each of which is adjustably positioned
a tube clamp 32, whose undersurface is recessed to
receive gasket 33 which retains the upper end of upright
glass tube 35. Clamp screw 36 threads down through
tube support 30 and operatively engages clamp 32 which
may be further secured by set screw 36'.

Valve body 12, FIG. 4, includes seat 37 and gasket 33'
seating the lower end of tube 35.

Seat 37 has an inlet 38 which projects down into intake
chamber 44, which has an inlet 43 in body 12.

Though a plurality of separately operated pressure
regulators are shown at 39, FIGS. 2 and 3, mounted upon
rear wall 26, only one such regulator is described in connection
with FIG. 4. Said pressure regulator is connected
with manifold 24 by conduit 40. Delivery conduit 41
connects pressure regulator 39 and inlet fitting 42 of
valve body 12 for supplying air under predetermined pressure
to intake chamber 44 through inlet 43. 65

2

Float 45, FIG. 4, is movably positioned within tube 35.
Axially arranged bumper 34 at the upper end of tube 35
is apertured to permit passage of air through passage 46 in
clamp 32 and out through return conduit 47, which returns
air to inlet 48 of valve body 12 and to delivery chamber 49.
Through fitting 50' said air passes through conduit 50 to gaging element 51 which has one or more leakage orifices 52. Each of the valve bodies 12 has an intake chamber 44, a delivery chamber 49, with connected gaging parts 50, 50', 51; conduits 41, 47; and tube 35.

A longitudinally apertured valve core 54 is snugly fitted
to the rear end of a bore B of the valve body 12 to co-operate
with valve sleeve 53 which is adjustably threaded into bore B of valve body 12 and which includes at its outer end on the exterior of the body a knob K for manual rotation. The inner end of valve sleeve 53 extends around a reduced part of valve core 54. Teflon plastic seals 64 are provided.

As shown, valve sleeve 53 has been rotated and moved
outwardly partially from core 54 to provide a by-pass aperture 55 by which some of the air delivered to intake chamber 44 is by-passed into delivery chamber 49 and does not pass upwardly through tube 35.

An air bleed valve includes spindle 56 which is threaded
within the bore of valve core 54, and is located within
valve sleeve 53, and outwardly thereof terminates in the
knurled adjusting head 57.

The inner tapered end 58 of spindle 56 projects into a
bore 59 of a valve seat 60 threaded into the rear end
of valve core 54 and sealed at 61. 30

The amount of air bleed is determined by rotative adjustment
of spindle 56—57 and the corresponding valve element 58 with respect to seat 60.

In the present construction and normally where there
are a series of bores or other part dimensions to be
checked on a workpiece such as the block of an engine or
the like, there are provided a series of gaging elements
51, one corresponding to each valve body 12 and tube
35 and float 45. 35

The air manifold 23, FIG. 4, provides a supply of air
under a predetermined pressure which may be used by
all of the gaging assemblies.

The air flows into intake chamber 44 and up through
tube 35, with float 45 therein responding to the movement
of air and thus by its position in tube 35 indicating
the rate of flow of air.

In order to visibly indicate this effect, due to air leaking
through gage element 51—52, there is provided a suitable
upright scale 64.

Side walls 18 mount brackets 65 at 66 for supporting
a background plate 67 behind tubes 35. Plate 67 mounts
spacers 68 which mount scales 64, 69, using fasteners
70.

Conclusion

It will be seen that the device includes a valve body
unit 10 FIG. 3, comprising separate valve bodies 12 connected
by pins 13—14, each valve body 12 containing valves 53 and 56; each body 12 having a tube 35 leading
to tube support 30; each body 12 having an air return conduit 47, an outlet conduit 50, and a gage element 51; and that cabinet side members 18 connect to and are connected by the valve body unit 10, tube support 30 and manifold 23; the latter having conduits 40—41, one set 40—41 for each body 12. 55

I claim:

1. A cabinet type multiple column gage comprising
a single elongated base;
an elongated sectional valve body unit horizontally
disposed and mounted on and secured to said base,
and comprising a plurality of separate short valve
bodies side by side and closely adjacent; with lock-

ing pins passing horizontally through these valve bodies to connect them to one another and thus form said valve body unit; with each valve body containing a bleed valve and a by-pass valve; 5 a horizontally disposed elongated single air tube support well above said valve body unit and parallel to it; vertical air tubes or columns, one for each valve body, connecting said valve body unit to said support; gage elements, one for each valve body; 10 outlet conduits, one for each valve body and each gage element, with each conduit connecting a valve body and a gage element; cabinet side members connected at their lower ends to the ends of and thus connected by said valve body unit; and connected at their upper ends to the ends of and thus connected by said support; an elongated single air supply manifold parallel to but alongside said valve body unit and having air supply conduits, one for each valve body, connecting the valve body unit to said manifold; 15 said manifold being connected at its ends to and thus connecting said side members.

2. The combination of claim 1 including air pressure regulators mounted on said base, one for each valve body connecting the valve body unit to said manifold.
